United States Patent Office.

WILLOUGHBY W. AND VARNUM J. PHILLIPS, OF WELLSVILLE, NEW YORK.

Letters Patent No. 63,421, dated April 2, 1867.

IMPROVEMENT IN MECHANISM FOR OPERATING THE PICKER-STAVES OF LOOMS.

The Schedule referred to in these Letters Patent and making part of the same.

TO ALL WHOM IT MAY CONCERN:

Be it known that we, WILLOUGHBY W. PHILLIPS and VARNUM J. PHILLIPS, of Wellsville, in the county of Alleghany, and State of New York, have invented a new and useful Improvement in Looms; and we do hereby declare that the following is a full and exact description thereof, reference being had to the accompanying drawings, and to the letters of reference marked thereon, in which—

Figure 1 is a top view of the loom.

Figure 2 is a sectional view, showing the parts used to operate the shuttle.

Figure 3 is a sectional view of the loom through the line *y y*, fig. 1.

Figure 4 is a detached view of the shaft *G*, figs. 2 and 3; and

Figures 5 and 6 are views of the changing beams used for different patterns.

Similar letters indicate like parts in all the figures.

The nature of our invention consists in an arrangement of ratchet-wheels, pawls, and cams to operate the shuttle.

To enable others skilled in the art to make and use our invention, we will proceed to describe its construction and operation.

A A is the frame of the loom, to which is pivoted at O O, (figs. 2 and 3,) the lay L, and to which motion is imparted in any convenient manner. B is the picker-staff, pivoted to the upright piece of the lay at *n*, fig. 2. D is an arm of the picker-staff, containing an elongated slot, *e*, in which works the bent part *b* of a rod, *m*, the other extremity of said rod being also bent at right angles to bear upon a cam, F, on a shaft, G, which has its bearings in the uprights of the lay. S is a spiral spring on the rod *m*, to force the foot of the rod upon the cam F. *a* is a rod connected to one extremity of the picker-staff B, the other end of said rod being attached to the picker C. P P are pawls hinged to the frame, and operating upon the ratchets R R on the shaft G when the lay is in motion. By means of the ratchets R R and pawls P P the shaft G is rotated when the lay is in motion, and the cams F F on said shaft are brought to operate upon the bent ends or feet of the rod *m*, giving motion to the picker-staff and picker in a backward direction, but when, by the further rotation of this shaft, the cam is removed from under the end of the rod, the spring S throws the rod down and drives the shuttle across the loom. The bent end *b* of the rod *m* enters an elongated slot, *e*, in the arm D of the picker-staff, which allows the picker to yield somewhat, and thus lessen the concussion consequent upon the meeting of these parts. *h h h*, fig. 1, are the treadles for operating the harness in conjunction with the tappets *t t*, situated on the shaft H, which has its bearings in the frame of the loom. The treadles have openings, *r r r*, in each of them, which permit the immediate upward motion of the harness when the tappets pass into said openings by the rotation of the shaft H. The tappet-shaft H is rotated by means of the pawls K K, pivoted to the uprights of the lay, engaging with the ratchet-wheels I I on the shaft H. A pawl, hinged to the frame of the loom, is also placed at each extremity of the shaft H, gearing into the ratchet-wheels I I, to prevent the backward movement of the shaft H. M N, figs. 5 and 6, are changing beams, in which the tappets are arranged to operate the treadles for different patterns. These beams are so constructed that when a different pattern is required, a beam, as H, may be removed and replaced by another. N, the journals of the different beams, fitting accurately the bearings in the frame of the loom. T is the cloth-beam, operated to wind up the cloth by the crank, U, in any convenient manner, and v is a ratchet-wheel, and W a pawl, fig. 3, to prevent the backward movement of the cloth-beam. X is the yarn-beam, having a ratchet-wheel, f, at one extremity, in which operates a pawl, g. *a'* is a let-off arm, hinged to one of the uprights of the frame, and connected at one end by the rod *c'* with the pawl *g*, which gears into the ratchet *f*, to prevent backward motion of the yarn-beam. When it is desired to wind up the cloth on the cloth-beam, by operating the end of the let-off arm next the cloth-beam, the pawl *g* is drawn away from the ratchet *f* and the yarn-beam is free to rotate, in order to permit the cloth to be wound upon the cloth-beam.

Having thus fully described our invention, what we claim as new, and desire to secure by Letters Patent, is—

We claim the ratchet-wheels R R, and pawls P P, in combination with the cams F F, bent rod *m*, spring S, picker-staff B, rod *a*, and picker C, for operating the shuttle, substantially as described.

WILLOUGHBY W. PHILLIPS,
VARNUM J. PHILLIPS.
